UNITED STATES PATENT OFFICE.

HERBERT I. WASHBURN, OF LAUREL SPRINGS, NEW JERSEY.

APPARATUS FOR GUIDING INDEPENDENTLY-MOVING ELEMENTS.

1,427,664.

Specification of Letters Patent. Patented Aug. 29, 1922.

Application filed August 21, 1917. Serial No. 187,495.

To all whom it may concern:

Be it known that I, HERBERT I. WASHBURN, of Laurel Springs, in the county of Camden and State of New Jersey, have invented certain new and useful Improvements in Apparatus for Guiding Independently-Moving Elements, whereof the following is a specification, reference being had to the accompanying drawings.

10 The invention relates to an apparatus and mechanism for guiding independently moving elements in a spiral course, and is particularly adapted for use in connection with agricultural implements, such as tractors and the like.

It is an object of the invention to provide an apparatus capable of guiding the independent element in a spiral of either increasing or decreasing radius.

20 A further object is to provide means whereby different rates of increase or decrease of the radius of the spiral may be produced.

In the embodiment of my invention here illustrated and described, there are a centrally mounted drum and flexible connecting or tether means, such as a wire, adapted to be attached to and to guide or control the moving element in its spiral course. As the 30 element moves the wire is either wound or unwound upon the drum, thereby either decreasing or increasing the effective length of tether and the radius of the spiral. Additional means are provided in connection 35 with the drum, in order to produce the proper spooling of the wire upon the drum, together with means for changing the rate at which the wire is wound upon the drum, whereby different distances may be produced between the volutes of the spiral.

40 In the accompanying drawings, Fig. I, is an elevation of an embodiment of my invention comprising a center post, drum and adjunctive parts adapted to be employed in connection with automatically operated agricultural tractors.

Fig. II, is a detail sectional view of a portion of the same upon an enlarged scale.

Fig. III, is a plan view of the parts illustrated in Fig. II.

45 Figs. IV, V, VI, and VII, are detail views in perspective of some of the elements embodied in my invention.

The apparatus consists generally of a centrally mounted drum, and means for either 55 rotating or locking the same, as desired, to-

gether with a centrally mounted guiding arm by which the spooling of the wire is controlled through the action of a threaded nut moving longitudinally on a screw 60 mounted axially of the drum.

Referring more particularly to the drawings, the apparatus consists of a hollow supporting tether post or pipe 1, mounted upon base 2, and rigidly supported by means of 65 stays 3, which are attached to arms 5, on crown piece 6.

Extending through the center of pipe 1, and projecting from either end thereof is shaft 7, which is provided at its upper end with pinion 17, and at its lower 70 end with a crank handle 9, capable of being engaged and held by catch 8, which is mounted on base 2, as shown in Fig. I.

Mounted in continuation of pipe 1, and surrounding the upper part of shaft 7, but free 75 to rotate about the same, is sleeve 10, which carries bracket 11, projecting laterally therefrom and which in turn carries sleeve 12. A smaller sleeve 13, extends centrally 80 through sleeve 12, and is free to rotate therein.

Sleeve 13, projects below and above sleeve 12, and is closed at its lower end by screw cap 14. Drum 15, is rigidly attached 85 to the upper projecting end of sleeve 13, by means of set screw 21, and is formed with an internal gear 16, adapted to mesh with pinion 17, for purposes hereinafter explained.

Mounted within sleeve 13, and capable of both rotation and longitudinal 90 reciprocation therein is tubular shaft 25, which carries at its upper end a horizontally 95 extending arm 30. This longitudinal reciprocation is controlled by screw 20, and threaded nut 22, mounted thereon. Screw 20, is held from rotation within sleeve 25, by means of lugs 19, which engage slots 18, in screw cap 14, see Figs. II, VI, and VII.

Nut 22, on the other hand, is rotatable on screw 20, but is united with the lower end of tubular shaft 25, by means of slots 26, formed in the end of the shaft, as shown in 100 Fig. IV, which engage projections 27, formed on screw 20, as shown in Fig. V.

Projections 27, extend upwardly from flange 23, which forms an abutment for the end of tube 25, so that tube 25, can only descend through the rotation of nut 22, on screw 20.

The connecting means by which the moving element is controlled consists, in the embodiment shown, of a wire 32, attached to 105 drum 15, which passes over pulley 31, carried by arm 30. This pulley supports the

110

wire and also serves the purpose of communicating any motion of the moving element to arm 30, and sleeve 25, which is attached thereto by set screw 29, for the purpose hereinafter described. Another pulley 36, is mounted in engagement with wire 32, beyond the end of arm 30, and is attached to arm 35, which is in turn pivotally attached at 33, to bracket 11, so that the same motion is transmitted to bracket 11.

In operation wire 32, is attached to the tractor or other independently moving element which it is desired to guide. As wire 32, is moved, arm 35, moves with it, causing sleeve 10, to rotate about shaft 7, and moving sleeve 12, in a circular path around the same center. During this operation, shaft 7, and pinion 17, are held locked by means of catch 8, and handle 9, so that if arm 35, and sleeve 12, rotate in a clockwise direction as shown by the arrow in Fig. III, the teeth of gear 16, engaging pinion 17, cause drum 15, to rotate independently in a counterclockwise direction. The extent of this rotation depends of course upon the ratio of pinion 17, and gear 16, and drum 15, moves a distance equal to the number of teeth on pinion 17, winding up that much of wire 32, as it goes. Consequently, with each rotation of drum 15, wire 32, is shortened an equal amount, so that the moving element is guided on a spiral of constantly decreasing radius. Such rotation of drum 15, therefore, is produced by the angular movement of the cable 32, with movement of the independently movable element tethered thereby, by means of arm 35, and the mechanism operated thereby.

The proper spooling of wire 32, on drum 15, is produced by the longitudinal motion of arm 20, through the action of screw 20, and nut 22. At the beginning of the operation in the case of a decreasing spiral the parts occupy the position shown in Fig. II, in which arm 32, is at such a height as to cause pulley 31, to guide wire 32, on the upper part of drum 15. The rotation of drum 15, however, also rotates sleeve 23, which is rigidly connected therewith by means of set screw 21. Cap 14, rotates with sleeve 23, thereby turning screw 20, by means of lugs 19, which engage slots 18, in cap 14, as already explained. During the rotation of screw 20, nut 22, is held from rotation by means of the engagement of projections 27, with slots 26, and is, therefore, caused to travel downwardly in accordance with the extent of the rotation and the thread on screw 20. This downward motion is proportioned to the extent of the rotation of the drum and results in lowering arm 30, and the proper spooling of wire 32, on drum 15.

The operation above described is the normal operation, but results in a very slight

decrease of the radius at each rotation. When it is desired to decrease the radius at a faster rate, I provide for increasing the rate at which the wire is wound upon the drum in the following manner: Bracket 40, projects from the lower end of sleeve 10, and is provided near its extremity with an aperture 41, which may be moved into opposition to aperture 42, in arm 43, which projects laterally from crown piece 6, and is always stationary. In this position arm 40, and, therefore, sleeve 10, may also be held stationary by inserting pin 45, in openings 41, and 42, thereby locking arms 40, and 43. In such position drum 15, is held from rotation about shaft 7, and also from rotation within sleeve 12, by means of pinion 7, which is locked by catch 8, and operates to prevent gear 16, from rotating. When drum 15, is so locked, pulley 36, and arm 35, are disconnected from wire 32, and each rotation of the moving element about the drum as a center therefore winds on drum 15, an amount of wire 32, equal to the periphery of the drum, thereby decreasing the radius to that extent at each rotation.

In this case the spooling operates in a slightly different manner for since drum 15, and consequently sleeve 23, are held stationary, screw 20, is also held stationary, but shaft 25, rotates with arm 30, thereby rotating nut 22, around the shaft and causing it to travel downwardly in the same manner as before, thus accomplishing the lowering of arm 30, and proper spooling of wire 32, on drum 15.

In case it is desired to start at the center and increase the radius of the spiral, wire 25, is wound on drum 15, which may be accomplished by rotating pinion 17, by handle 9, until the wire is completely wound and the parts occupy the positions in which they will be found at the end of the operation as first described. The moving element is in this case moved in the opposite direction and the wire unwound from the drum, the parts operating reversely to provide the unwinding of the wire and raising of arm 30, so that pulley 31, will always be at the proper height to guide wire 32, as will be obvious to those skilled in the art.

In order to provide for the proper lubrication of the parts, shaft 25, may be lifted entirely out of sleeve 23, and the desired quantity of oil or lubricating medium placed within the opening. This is rendered possible by the slotted connection by which sleeve 23, engages nut 22. After the oil has been inserted, the longitudinal travel of nut 22, during the operation of the apparatus, causes an even distribution of the oil, which results in a very efficient and simple system of lubrication.

It is obvious that my apparatus may be used in connection with any form of moving

element which it is desired to guide in a spiral course, and further, that changes may be made in construction and arrangement of parts without departing from the spirit of 5 the invention.

Having thus described my invention, I claim:

1. Apparatus for guiding a tethered moving element comprising a tether post element, a tether and means, actuated by angular movement of the tethered element about said tether post element, for varying the length of tether so as to limit the moving element, when at the extreme of its tether, to 15 a spiral course.

2. Apparatus for guiding a tethered moving element comprising a tether post element; a drum associated therewith; and means for rotating said drum to wind the 20 tether cable thereon actuated by angular movement of the tethered element about said tether post element to decrease the length of the tether at a constant rate, so as to limit the moving element to a spiral course of constantly diminishing radius when moving in 25 one direction around said tether post element at the extreme of the tether.

3. Apparatus for guiding a tethered moving element comprising a tether post element; 30 a drum associated therewith; means for rotating said drum to wind a tether cable thereon actuated by angular movement of the tethered element about said tether post element to decrease the length of the tether at a constant rate, so as to limit the moving element to a spiral course of constantly diminishing radius when moving in one direction around said tether post element at the extreme of the tether; and means for spooling the tether 35 upon said drum.

4. Apparatus for guiding a tethered moving element comprising a tether post element; a rotary winding drum for the tether cable associated with said tether post element; and means operable by the angular movement of said cable with movement of the moving element angularly about said tether post element for rotating said drum to alter the effective length of tether. 45

5. Apparatus for guiding a tethered moving element comprising a tether post element; a rotary drum for the tether mounted to revolve about an eccentric point; means for causing said drum to revolve about said 50 point actuated by angular movement of the tethered element about said tether post element; and means for causing said drum to revolve as it rotates, so as to alter the length of tether cable wound thereon and thus vary the effective length of tether.

6. Apparatus for guiding a tethered moving element comprising a tether post element; a rotary drum for the tether mounted to revolve about an eccentric point; means 55 for causing said drum to revolve about said

point actuated by angular movement of the tethered element about said tether post element; means for causing said drum to revolve as it rotates, so as to alter the length of tether cable wound thereon and thus vary 70 the effective length of tether; and means controlled by the rotation of the drum for spooling the tether cable thereon.

7. Apparatus for guiding a tethered moving element comprising a tether post element; a rotary drum for the tether mounted to revolve about an eccentric point and having an internal gear thereon; a gear pinion meshing with said internal gear; means for causing said drum to revolve about said 75 point actuated by angular movement of the tethered element about said tether post element; and means for holding said gear pinion stationary to cause said drum to rotate as it revolves, so as to alter the length of 80 tether cable wound thereon and thus vary the effective length of tether.

8. Apparatus for guiding a tethered moving element comprising a tether post element; a rotary winding drum for the tether 90 cable associated with said tether post element; and means for rotating said drum and spooling the tether cable thereon actuated by angular movement of the tethered element about said tether post element. 95

9. Apparatus for guiding a tethered moving element comprising a tether post element; a rotary winding drum for the tether cable associated with said tether post element; means for rotating said drum actuated by angular movement of the tethered element about said tether post element; guide means for the tether cable; and means for causing said guide means to travel longitudinally of said drum to spool the cable thereon, comprising a screw and nut co-axial with said drum, one attached to said drum and the other to said guide means. 100

10. Apparatus for guiding a tethered moving element comprising a tether post element; a rotary winding drum for the tether cable associated with said tether post element; means for rotating said drum actuated by angular movement of the tethered element about said tether post element; 110 means for guiding and spooling the tether cable including an arm engaged therewith and a sleeve attached to said arm mounted co-axial with said drum; a screw also mounted co-axial with said drum and connected to revolve therewith, and a nut threaded on said screw engaged with said sleeve, so that rotation of said arm with angular movement of the tether cable shall cause it to move axially thereof. 115

11. Apparatus for guiding a tethered moving element comprising a tether post element; a rotary winding drum for the tether cable associated with said tether post element; means for rotating said drum actu- 120

ated by angular movement of the tethered element about said tether post element; means for guiding and spooling the tether cable including an arm engaged therewith and a sleeve attached to said arm mounted co-axially with said drum, a second sleeve attached to said drum surrounding that first mentioned, with a cap on the end thereof, a screw mounted in said second sleeve and 10 engaged with said cap so as to rotate with said second sleeve, and a nut threaded on said screw connected to said first mentioned sleeve, so that rotation of said arm with angular movement of the tether cable shall 15 cause it to move axially thereof.

12. Apparatus for guiding a tethered moving element comprising a tether post element; a rotary winding drum for the tether cable associated with said tether post element; means for rotating said drum actuated by angular movement of the tethered element about said tether post element; means for guiding and spooling the tether cable including an arm 20 engaged therewith and a sleeve attached to said arm mounted coaxially with said drum, a second sleeve attached to said drum surrounding that first mentioned with a slotted cap mounted in the end thereof, a screw 25 mounted in said second sleeve and having lugs in engagement with said cap so as to cause it to rotate with said second sleeve, and a nut threaded on said screw connected to said first mentioned sleeve, so that rotation 30 of said arm with angular movement of the tether cable shall cause it to move axially thereof.

13. Apparatus for guiding a tethered moving element comprising a tether post element; a bracket revolvably mounted on 40 said tether post element; a drum for the tether cable rotatably mounted on said bracket; and means actuated by angular movement of the tethered element about said 45 tether post element for causing said bracket to revolve and thereby causing said drum to rotate, so as to alter the length of tether cable wound upon the drum and thus vary the effective length of tether.

14. Apparatus for guiding a tethered moving element comprising a tether post element; a bracket revolvably mounted on said tether post element; a drum for the tether cable rotatably mounted on said bracket; means 55 actuated by angular movement of the tethered element about said tether post element for causing said bracket to revolve and thereby causing said drum to rotate in the opposite direction to that of the revolution 60 of the bracket, so as to alter the length of tether cable wound upon the drum and thus vary the effective length of tether; and means actuated by angular movement of the tether cable about the tether post element 65 for spooling it upon said drum.

15. Apparatus for guiding a tethered moving element comprising a tether post element; a bracket revolvably mounted on said tether post element; a drum for the tether cable rotatably mounted on said bracket having an internal gear thereon; means actuated by angular movement of the tethered element about said tether post element for causing said bracket to revolve; and a pinion on said tether post element 70 meshing with said internal pinion on the drum for causing the drum to rotate in a direction opposite to the direction of revolution of the bracket, so as to alter the length of tether cable wound upon the drum 75 and thus vary the effective length of tether.

16. Apparatus for guiding a tethered moving element comprising a tether post element; a bracket revolvably mounted on said tether post element; a drum for the tether cable rotatably mounted on said bracket having an internal gear thereon; means actuated by angular movement of the tethered element about said tether post element for causing said bracket to revolve; a pinion on 80 said tether post element meshing with said internal pinion on the drum for causing the drum to rotate in a direction opposite to the direction of revolution of the bracket, so as to alter the length of tether cable wound upon the drum 85 and thus vary the effective length of tether; means for locking said pinion against rotation to cause revolution of said drum as aforesaid, or releasing it; and means for locking said bracket 90 against revolution.

17. Apparatus for guiding a tethered moving element comprising a tether post element; a bracket revolvably mounted on said tether post element; a drum for the tether cable rotatably mounted on said bracket; and means actuated by angular movement of the tethered element about said tether post element for causing said bracket to revolve and thereby causing said drum to rotate in the opposite direction to that of the revolution of the bracket, so as to alter the length of tether cable wound upon the drum and thus vary the effective length of tether, 105 said means comprising an arm attached to 110 said bracket and engaging the tether cable.

18. Apparatus for guiding a tethered moving element comprising a tether post element; a bracket revolvably mounted on said tether post element; a drum for the tether cable rotatably mounted on said bracket having an internal gear thereon; means actuated by angular movement of the tethered element about said tether post element for causing said bracket to revolve and thereby 120 causing said drum to rotate; and means for rendering said last mentioned means inactive and for locking said bracket against revolution.

19. Apparatus for guiding a tethered 125

moving element comprising a tether post element; a bracket revolvably mounted on said tether post element; a drum for the tether cable rotatably mounted on said bracket; 5 means including an arm engaging said cable actuated by angular movement thereof with movement of said moving element angularly about said tether post element for causing said drum to revolve and thereby causing 10 said drum to rotate; and means for rendering said last mentioned means inactive and for locking said bracket against revolution.

20. Apparatus for guiding a tethered moving element comprising a tether post element; a bracket revolvably mounted on said tether post element; a drum for the tether cable rotatably mounted on said bracket; 15 means including an arm engaging said cable

actuated by angular movement thereof with movement of said moving element angularly 20 about said tether post element for causing said drum to revolve and thereby causing said drum to rotate; means for rendering said last mentioned means inactive and for locking said bracket against revolution; and 25 means for guiding and spooling said tether cable actuated by angular movement of the cable as aforesaid and by rotation of the drum.

In testimony whereof, I have hereunto 30 signed my name, at Philadelphia, Pennsylvania this eighteenth day of August 1917.

HERBERT I. WASHBURN.
